UNITED STATES PATENT OFFICE.

JOSEPH LANTAGNE, OF CENTRAL FALLS, RHODE ISLAND.

ARTICLE OF STORE FURNITURE.

No. 847,484.

Specification of Letters Patent. Patented March 19, 1907.

Application filed December 14, 1905. Serial No. 291,770.

To all whom it may concern:

Be it known that I, JOSEPH LANTAGNE, a citizen of the United States, residing at Central Falls, in the county of Providence and State of Rhode Island, have invented certain new and useful Improvements in Articles of Store Furniture; and I do declare the following to be a full, clear, and exact description of the invention, such as will enable others skilled in the art to which it appertains to make and use the same.

My invention relates to improvements in articles of furniture and more particularly to that class used by butchers and other merchants in markets, stores, and the like.

The object of the invention is to provide a simple, inexpensive, durable, and efficient refrigerator of this character in which its contents may be readily moved out of the same upon sliding tables or supports when it is desired to cut or otherwise handle said contents.

With the above and other objects in view the invention consists of certain novel features of construction, combination, and arrangement of devices, as will be hereinafter described and claimed.

In the accompanying drawings, Figure 1 is a front elevation of a refrigerator constructed in accordance with my invention. Fig. 2 is an end elevation of the same with parts in section. Fig. 3 is a detail vertical transverse sectional view. Fig. 4 is a detail vertical longitudinal sectional view, and Fig. 5 is a detail horizontal sectional view.

Referring to the drawings by numeral, 1 denotes the body or casing of the refrigerator, which may be of any form and construction, but which is here shown as supported upon a suitable base 2. The body or casing 1 is of substantially rectangular form and is divided centrally by a horizontal partition 3 into an upper ice compartment or chamber 4 and a lower compartment or chamber 5, in which the meats, dairy products, vegetables, fruits, or other food or material to be preserved are placed. Suitable doors 6 are provided, preferably at the ends of the compartment 4, so that the latter may be filled with ice, and suitable drain connections are also provided for carrying off the water. The cold air in the upper compartment 4 passes downwardly through the latter through openings in the partition 3 and circulates in the compartment 5. The food or other sub-

stance placed in the latter is supported upon sliding tables or supports 7, which are adapted to be moved into and out of the body or casing 1 through its front, which is closed by a plurality of doors 8. The tables or supports 7 are preferably and as here shown of rectangular form and are mounted to slide forwardly and rearwardly in T-shaped guides 9, secured upon the bottom 10 by bolts or the like 11 and having their flanged upper portions 12 overhanging the side edges of the tables or supports 7, which slide between them, as clearly shown in Fig. 4 of the drawings. The tables or supports 7 preferably rest and slide upon supporting-rollers 13, which are arranged at suitable intervals adjacent to the guides 9 and have their journals 14 mounted in ball-bearings 15, arranged in recesses 16, formed in the bottom 10, as seen in Fig. 4.

In order to support the front or outer edge of the tables 7 when the latter are moved out of the compartment 5 through its open front, I preferably provide each of them with a supporting-leg 17. The latter is secured by means of an angle-bracket 18 or any other suitable fastening in a recess formed in the center of the front edge of one of the tables 7 and has upon its lower end a caster-wheel or the like 19, which runs upon the floor or other support.

The doors 8 may be of any desired form and construction; but I preferably mount them so that they slide vertically in guides 20, arranged at the front ends of the guides 19, between the bottom 10 and the front portion of the upper compartment of the body. As clearly shown in Fig. 5 of the drawings, the sash-frames 21 of the doors slide in the opposite channeled faces of the guide-strips 20, and they are covered by a double layer of glass or other transparent material 22, so that the contents of the refrigerator may be inspected without raising the doors. By mounting the doors 8 so that they slide vertically, as shown, any one may be elevated, so that the table 7 in rear of the same may be drawn out of the compartment 5, and said door may be then lowered to prevent the escape of cold air from and the entrance of hot air into the refrigerator, while the meat or other food upon the extended table may be cut, chopped, or otherwise handled. To permit the table 7 to be moved into the compartment 5, so that it will not interfere with

the closing of the door 8, the bottom 10 is recessed, as shown at 23, to receive the supporting-leg 17.

From the foregoing description, taken in connection with the accompanying drawings, the construction, use, and advantages of the invention will be readily understood without requiring a more extended explanation.

Various changes in the form, proportion, 10 and the minor details of construction may be resorted to without departing from the principle or sacrificing any of the advantages of the invention as defined by the appended claim.

Having thus described my invention, what I claim as new, and desire to secure by Letters Patent, is—

An article of furniture having a plurality of compartments disposed side by side and having a common bottom, the outer end of which projects from said compartments and is pro-

vided with recesses, T-shaped guides secured on the bottom, between the compartments, vertical guides at the outer ends of the T-shaped guides and also between the compartments, tables in the bottoms of the compartments, separated, and having their side edges partly overlapped by the T-shaped guides and each having a supporting-leg movable therewith and fitting in one of said recesses in the bottom, when the table is moved into its compartment, and vertically-movable doors for the compartments operating in the vertical guides, substantially as described.

In testimony whereof I have hereunto set my hand in presence of two subscribing witnesses.

JOSEPH LANTAGNE.
